(57) **CLAIM**

The ornamental design for a handle for a medical gas/fluid regulator or conserver, as shown and described.

DESCRIPTION

FIG. 1 is a perspective view of a handle of the present invention;

FIG. 2 shows a front view of the handle of FIG. 1;

FIG. 3 shows a rear view of the handle of FIGS. 1 and 2;

FIG. 4 shows a left side view of the handle of FIGS. 1 and 2;

FIG. 5 shows a right side view of the handle of FIGS. 1 and 2;

FIG. 6 shows a top view of the handle of FIGS. 1 and 2; and,

FIG. 7 shows a bottom view of the handle of FIGS. 1 and 2.

The broken lines show portions of a medical gas/fluid regulator or conserver attached to the handle that form no part of the claimed design.
